Application August 8, 1932, Serial No. 627,962
In Germany August 17, 1931

3 Claims. (Cl. 226—2)

Our invention relates to packing machines and more particularly to machines for packing fragile articles such as incandescent lamps. One of the objects of our invention is to provide a machine 5 for cartoning articles which will be fully automatic in operation, including the opening and forming of flat folded cartons, the placing of a liner therein, the insertion of the object to be packed, and the closing up of all of the flaps 10 of the carton. Another object is to provide novel means for receiving and positioning fragile articles such as electric incandescent lamps, which will be delicate and accurate in operation.

According to our invention, cartons are transferred to holding jaws of a rotatable table from 15 a container in which they are stored in a folded position, said cartons being opened during said transfer. During subsequent rotation of the table the bottom flaps of the carton are closed up 20 by mechanism mounted adjacent to the path of travel of said table. Liners are inserted in the cartons by mechanism comprising a suction head which pulls a liner out of a container and supplies it to a pair of rotatable jaws which roll up 25 said liner and then move therewith toward the carton. The article to be packed is then inserted in the carton by a feed mechanism which permits the intermittent ejection of a single article of a group and the top flaps of the carton 30 are closed.

In the drawings Fig. 1 is a fragmentary plan view of the device comprising our invention; Fig. 2 is an elevation of a carton supply mechanism; Fig. 3 is a perspective view of a carton; Fig. 4 is a detail view in perspective of carton selecting mechanism; Fig. 5 is a detail plan view of 35 carton opening mechanism; Fig. 6 is a front elevation of bottom flap closing mechanism; Fig. 7 is a side elevation of mechanism for closing the bottom ear flap and slotted flap and Fig. 8 is a detailed side elevation to a larger scale showing 40 this mechanism in the closed position; Fig. 9 is a front elevation of mechanism for securely setting the bottom flaps in a closed position; Fig. 10 is a side elevation of a liner supply mechanism and Fig. 11 is a plan view thereof; Fig. 45 12 is a side elevation of a liner squaring mechanism and Fig. 13 is another side elevation of said mechanism in another position; Fig. 14 is a plan view of mechanism for feeding the articles 50 to be packed to the cartons and Fig. 15 is a side elevation thereof; Fig. 16 is a section through the line I—I of Fig. 15; Fig. 17 is a section through the line II—II of Fig. 15; Fig. 18 is a front elevation of top flap closing mechanism; Fig. 19 is

a side elevation of a top flap tongue bending mechanism; Fig. 20 is a side elevation showing an elongated shaping strip for partially closing the tongue flap; and Fig. 21 is a side elevation of tongue flap closing mechanism.

Referring to Figs. 1 and 2, cartons 10 are stored in a folded vertical position on a table 11, being held between a pair of rails 12 which are mounted on vertical supports 13 which are in turn adjustably mounted on pins 14 in the table 10 11. Said cartons 10 are held between lips 15 (Fig. 4) on the forward edges of the rails 12 and a movable plate 16. Said plate 16 is mounted on a bearing 17 which is slidably mounted on a bar 18 which is mounted in a bracket 19 15 on the table 11 and in a lug 20 on a vertical bearing 21 which is mounted on the table 11. The plate 16 is held against the stack of cartons 10 by a weight 22 (Fig. 2) which is attached to a string 23 which is also attached to the bearing 17 and runs over a pulley 24 mounted on a pin 25 in the bearing 21.

The carton 10 (Fig. 3) comprises two plain top flaps 26, 27, a third top flap 28 having a tongue 29, two plain bottom flaps 30, 31, an ear flap 32 25 35 having ears 33 and a slotted flap 34 having slots 35 corresponding to the ears 33.

The carton selecting mechanism (Fig. 2) comprises a vertically disposed blade 36 mounted on a cross arm 37 which is mounted on a vertical 30 shaft 38 passing through the bearing 21. The shaft 38 is lowered by mechanism not shown so that the blade penetrates into the first of the group of cartons located inside of the rails 12 (Fig. 4) and then said shaft 38 and blade 36 are 35 rotated approximately 60 degrees bringing the carton into position between a pair of jaws 39 (Figs. 1 and 5). Said jaws 39 are mounted on arms 40 which are pivotally mounted on pins 41, 42 in the table 11. An arm 43 having a slot 44 40 therein is mounted on the pin 42 and a lever having arms 45, 46 is mounted on the pin 41, the arm 45 having a pin 47 therein which engages the slot 44 in arm 43. When a carton has been brought between the jaws 39 they are drawn together by a spring 48 on the arm 46 until said arm 46 strikes a stop 49, thereby opening the folded carton. As the blade 36 is lowered to select another carton, a second blade 50 mounted on a cross arm 51 which is preferably mounted on the shaft 38, is lowered into the opened carton being held in the jaws 39. Upon rotation of the shaft 38 said blade 50 carries a carton from the jaws 39 to a pocket 52 at position A on a rotatable table 53. The table as shown in Fig. 1 has twenty-four 55

such pockets 52, the corresponding positions being lettered A to Y. In passing to the pocket 52, the carton is drawn between a pair of rails 54 which guide said carton into said pocket and also 5 press the carton perpendicular to its previous closed position to give it a set in the open position. The jaws 39 are opened to release the carton by a pin 55 which is moved by mechanism not shown. The carton will be held in the pocket 52 quite 10 firmly although, if desired, vacuum lines may be connected to the back walls thereof to more firmly hold said cartons.

At position B a squaring-off plate 56 is mounted on a rod 57 which is disposed radially to the table 15 53 and slides in a bearing 58. Said rod 57 is connected with the machine drive so that after each indexing motion of said table 53 it moves forward and squares up a carton in the pocket 52.

At position C the bottom flap 31 (Fig. 6) is 20 closed by a pressure plate 59 disposed below the pocket 52. Said plate 59 is pivotally mounted on a pin 60 in a vertically disposed rod 61. Said rod 61 is slidably mounted in a sleeve 62 which carries a collar 63 at its upper end. Said collar 25 63 rests on a cross arm 64 mounted on a rod 65 which is slidably mounted in a bracket 66. A yoke 67 is mounted at the bottom of the rod 61 and straddles the rod 65 and a spring 68 is connected to the bottom of said rod 61 and to the 30 cross arm 64. A link 69 mounted on the plate 59 and collar 63 serves to support said plate. To fold the flap 31, the rod 65 is moved upward carrying the plate 59, rod 61 and sleeve 62 therewith. Said plate 59 strikes the flap 31 and folds it in. 35 and when the upper part of said plate 59 has reached the lower level of pocket 52, the yoke 67 strikes the bracket 66, restraining the rod 61 from further upward movement, but the rod 65 with cross arm 64 continues to move up against 40 the pull of the spring 68 thereby raising the collar 63 and link 69 and bringing the plate 59 with the flap 31 up to a horizontal position. The top flap 26 is opened outward to facilitate insertion of the article to be packed by the swinging of a 45 cross bar 70 mounted on a bent rod 71. Said rod 71 is pivotally mounted on a pin 72 in a support 73. Said pin 72 is revolved by an arm 74 which is connected by a pin 75 to a reciprocating rod 76.

As the carton moves to position D, the upper 50 flap 27 is folded outward by an upturned edge 77 of a horizontally disposed segment shaped rail 78 which is located immediately above the pockets 52 and extends over several positions, as shown in Fig. 1. The outwardly opened flap 26 also 55 passes under the rail 78 which serves to retain flaps 26 and 27 in the opened position. A shorter rail 79 disposed below the pockets 52 has a downwardly turned edge 80 which serves to fold up the bottom flap 30 and guide said flap 30 and 60 flap 31 onto said rail 79. That portion of lower rail 79 extending across the pocket 52 comprises two strips 81 (Figs. 6 and 7). A plunger 82 located below the pocket in position D is slidably mounted in a bracket 83 and carries a cross arm 65 84. A pair of levers 85, 86 are pivotally mounted on a pin 87 in the bracket 83 and have slots 88, 89 which cooperate with pins 90, 91 on the collar 84. When the plunger 82 is moved up, the levers 85, 86 are brought together. Due to the shape of 70 the slots 88, 89 and the length of the levers 85, 86, the lever 86 is swung in faster than the lever 85 so that a jaw 92 thereon folds in the bottom slotted flap 34 and subsequently a jaw 93 on the lever 85 folds in the ear flap 32. As the plunger 82 continues to advance upward the jaws 92, 93 are

held in the closed position by the pins 90, 91 which engage the elongated straight portions of the slots 88, 89, and a pair of blades 94 on the upper part of the plunger 82 fold the ears 33 about the jaw 92, which acts as a mandrel, and insert said ears in the slots 35 (Fig. 8). The plunger 82 is then lowered to withdraw the jaws 92, 93.

The carton is moved to position E where a plunger 95, located below the pocket 52, reciprocates in a bearing 96. Said plunger 95 carries 10 a pressure plate 97 on the upper part thereof on which are located bosses 98. When the plunger 95 is moved upward, said bosses 98 strike the bottom of the carton, thereby completely closing the ears 33 and pressing all of the bottom flaps firmly 15 together.

The carton, having the bottom closed, passes position F and enters position G opposite which is located a container 99 (Figs. 10, 11) in which corrugated paper liners 100 are stored. Said container 99 is mounted on a plate 101 which is mounted on a stationary cover plate 102 of the table 53. The liners 100 are held forward in the container by a weighted plate 103 against clips 104 and small rollers 105 at each side and a 20 larger roller 106 in the middle which are mounted on the plate 101. The foremost liner 100 in said container 99 is pulled past the rollers 105 and clips 104 and curved about the center roller 106 by suction heads 107 which swing out on levers 25 108. Said levers 108, which are pivotally mounted on pins 109 and pass through slots 110 in the plate 101 are actuated by a cord 111 and springs 112. One of the ends of the liner 100 is placed between a pair of semi-cylindrical jaws 113, 114 30 35 by the suction head 107. The jaw 113 is rigidly mounted in a sleeve 115 comprising the lower part of a shaft 116 which is rotatably mounted in a bracket support 117 mounted on the cover plate 102. The jaw 114 is pivotally mounted on a pin 40 118 in the sleeve 115 and is held open against the pull of a spring 119 by a rod 120 mounted on said jaw and located inside of the sleeve 115. Said rod 120 carries a cross pin 121 at the upper end which passes through slots 122 in the sleeve 45 115 and rests on a collar 123 mounted on a sleeve 124 which is slidably mounted on the sleeve 115. A gear 125 mounted on the upper part of the shaft 116 meshes with a gear 126 mounted on a shaft 127 which is rotatably mounted in a bearing 128. 50 The sleeve 124 with collar 123 is held up by an arm 129 of a sleeve 130 which is slidably mounted on the bearing 128 and is actuated by a rod 131. Immediately after the end of the liner 100 has been inserted between the open jaws 113, 114, the 55 rod 131 is lowered, thereby pulling down the sleeve 130 and collar 123 and sleeve 124. The pin 121 then drops down the slot 122 and the rod 120 is lowered thereby allowing the spring 119 to pull the jaw 114 down against the jaw 113. The 60 jaws 113, 114 are then rotated by revolving the rod 127 which rotates the gears 126 and 125 and shaft 116 which carries said jaws on its lower sleeve portion 115. The vacuum in the heads 107 is broken when the jaws have clamped 65 the liner 100 so that said liner is rolled up around said jaws and held there by a cylinder 132 mounted concentrically to said jaws on the plate 101. During further downward movement of the sleeve 124, the jaw 114 is separated from the jaw 113 by 70 a wedge 133 mounted on said sleeve 124, thereby releasing the liner 100 which is then pushed through a hole 134 in the rail 78 into the carton 10.

No operation is performed at position H. At po- 75

sition J the liner 100 (Fig. 12) is definitely located in the bottom of the carton 10 which is supported by a horizontal rail 134 located immediately below the pockets 52 and extends over several of the following positions. The location of the liner 100 is performed by a pressure plate 135 which is mounted on a vertical rod 136 which is slidably mounted in a sleeve 137. Said sleeve 137 is slidably mounted in a bracket 138 and is actuated by a bar 139 which is mounted on a collar 140 on said sleeve 137. The rod 136 and sleeve 137 are prevented from turning by a screw 141 which is mounted in the bracket 138 and engages slots 142 in said rod and sleeve. Said rod 136 and sleeve 137 are resiliently coupled by a spring 143 connected to the collar 140 and a pin 144 on the top of said rod 136. An arm 145 on said sleeve 137 carries a pin 146 which engages a slot 147 in a lever 148 pivotally mounted on a pin 149 in the rod 136.

The articles to be packed, incandescent lamps 150, (Fig. 15) are stored at position K in an inclined gravity feed chute 151 which is mounted on a bracket 152 which is mounted on a bearing sleeve 153 supported by a fixed bracket 154. The chute 151 terminates in a vertical cylindrical portion 155 further supported by a bracket 156. As the lamps 150 are released one at a time by mechanism hereinafter described, they drop into said cylindrical portion 155 and come to rest on a plurality of resilient cushioning fingers 157 which are mounted on pins 158 on the cylinder 155 and project through slots 159 in said cylinder. Said fingers are held in by leafsprings 160 mounted on the cylinder 155. The lamp 150 is held upright by a pair of V-shaped fingers 161 which project through slots 162 in the cylinder 155 and grip the neck of said lamp, being held thereagainst by a spring 163 connecting said fingers. Said fingers 161 are mounted on arms 161' which are pivotally mounted on a pin 162' in the cylinder 155. The mechanism for inserting the lamp into the carton 10 comprises a tube 164 disposed vertically above the cylinder 155 and having a bell-shaped end 165 with a cooperating lever 166 pivotally mounted on a pin 167 in said tube 164.

The lower end of said lever 166 projects into said bell 165 through a slot 168 and is held therein by a spring 169 mounted on the upper leg of said lever and on a lug 170 on the sleeve 164. A prong 171 on the upper end of the lever 166 projects through a slot 172 in the tube 164 into a notch 173 in a bar 174 located inside of said tube 164. A pin 175 on said bar 174 rides in a slot 176 in the tube 164 and said bar and tube are resiliently connected by a spring 177 mounted on a collar 177' on said tube 164 and on a lug 178 on said bar 174 which projects through a slot 179 in said tube. Said tube 164 is mounted on a cross arm 180 which is mounted on a vertically disposed shaft 181 which is slidably mounted in the sleeve 153. The cross arm 180 slides over a vertical rod 182 in the bracket 156 to maintain the proper alignment of tube 164. To insert the lamp 150 in the carton 10 the sleeve 164 is lowered by means of the shaft 181, and the bell 165 settles over the base of the lamp 150, the lever 168 bearing against the side of said base and gripping it securely. Immediately thereafter, a wedge shaped head 183 of an arm 184 pivotally mounted on a pin 185 in the bracket 154, is moved down, engaging a pair of rollers 186 on the arms 161' and thereby spreading apart the fingers 161 to release the bulb 150. Said arm 184 is pivoted by a bar 187 which is connected to an arm 188

mounted on the pin 185. The bell 165, with the base of the lamp 150 securely clamped therein, continues to move down, pushing said lamp past the fingers 157 against the pressure of the comparatively weak springs 160. Just before the lamp reaches the bottom of the carton 10, the pin 175 on the bar 174 strikes an arm 189 thereby restraining said bar from further downward movement. The bent end 171 of the lever 166 slides out of the notch 173 on to the bar 174, thereby causing the lower end of said lever 166 to be withdrawn from the bell 165, releasing the base of the lamp 150. In the subsequent upward movement of the tube 164 and bell 165, the finger 171 re-enters the notch 173 to carry the bar 174 along.

The intermittent feed mechanism comprises two cooperating stop arms 190, 191 provided with soft pads 192, 193 respectively. The arm 190 is pivotally mounted on the lever 189 which is mounted on a pin 194 in a bracket 195 mounted on the sleeve 153. The arm 191 is mounted on a lever 196 which is pivotally mounted on the pin 194. The lower end of the lever 196 is held by a spring 197 against a roller 198 (Figs. 12 and 13) on a horizontally disposed rod 199 which is slidably mounted in lugs 200 on a bracket 201. When the liner locating mechanism is in the position shown in Fig. 13, the stop arm 191 is in the down position, holding back the row of lamps 150 in the chute 151 and a lamp is located in the lower cylindrical portion 155 (Fig. 15) of the chute. As the bell 165 moves down to insert said lamp 150 in the carton 10, the arm 189, bearing against the pin 167, is pivoted downward by a spring 202 until a lug 202' thereon strikes a stop screw 203, thereby setting the stop arm 190 in the path of the lamps 150 as shown in Fig. 12. The bar 139 and sleeve 137 (Fig. 13) are also moved down and after the pressure plate 135 strikes the liner 100, said sleeve 137 continues to move down causing the arm 145 to pivot the lever 148 about the pin 149. A finger 203 comprising part of the lever 148 is pivoted to the right against a roller 204 on the rod 199 thereby pivoting the lever 196 in a counter-clockwise direction and lifting the lever 191 from the foremost of the lamps 150 in the chute 151, allowing said lamps to move down against the stop arm 190. When the sleeve 137 and rod 136 move up again the arm 191 pivots down again to the position shown in Fig. 13 while the bell 165 (Fig. 15) moves up, the pin 167 thereon engaging the arm 189 and pulling the stop arm 190 up to allow another bulb to drop into the cylinder 155. In the event there is no liner in the carton in Figs. 12 and 13, the plate 135 will not be stopped but will continue to move down with the sleeve 137 so that the finger 203 will not be pivoted but will remain in the position shown in Fig. 13. In that case the rod 199 will remain in the position shown in Fig. 13 as will the stop arm 191, so that no lamp will be delivered to the cylinder 155, thereby preventing the packing of a lamp in a carton that has not been supplied with a liner.

No operation is performed at position L. Above position M is located an angular arm 204 (Fig. 18) which is mounted so as to pivot to the right, a cross pin 205 thereon engaging the top flap 27 and folding it inward. As the carton is moved to position N the flap 26 is folded down by an upwardly projecting end 206 of a rail 207 located above the pockets 52. Above position O is located a horizontally disposed stationary blade 208 and a movable blade 209 which slides over said blade

208 to bend down at a right angle the tongue 29 of the flap 28. The cartons may be stamped with the date or other data at position P, no mechanism being shown.

5 5. A stationary curved guide rail 210 (Fig. 20) is located over positions Q and R to bend the flap 28 down from its vertical position to a slanted position.

Above position S is located mechanism for closing the tongue flap 28 comprising a knife blade 211 vertically disposed above the wall of the carton opposite to said flap 28 and mounted on a cross arm 212 which is mounted on a vertically disposed bar 213. Said bar 213 is slidably mounted in a sleeve 214. A pressure plate 215 is pivotally mounted on a pin 216 on a lug 217 on the sleeve 214. A roller 218 on the end of said plate 215 is held against the cross arm 212 by a spring 219 mounted on said plate 215 and pin 220 on the lug 217. As the cross arm 212 is moved down by the bar 213, the blade 211 penetrates into the carton 10 along the back wall thereof, and the plate 215 is pushed down against the flap 28. The tongue 29 slides along the blade 211 into the carton 10, thereby completing the closing up of the carton.

30 Signaling devices which are not shown may be arranged at positions T, U, V to check the closing of the cartons and bring attention to those which are not properly closed.

The cartons are dislodged from the pockets 52 in position W by a plunger 221 which is located above said pocket and moves vertically downward. Said cartons drop on to an endless belt 5. 222 by which they are removed.

What we claim as new and desire to secure by Letters Patent of the United States, is:

1. In a device of the class described, an inclined

chute for feeding articles, cooperating fingers, means for actuating said fingers to feed said articles one by one, a chamber at the foot of said chute, resiliently mounted fingers projecting into said chamber adapted to intercept and support said articles, a transfer arm, and means for moving said transfer arm to grip said article and carry it through said chamber to a carton disposed adjacent thereto.

2. In a device of the class described, an inclined chute for feeding articles, cooperating fingers, means for actuating said fingers to feed said articles one by one, a chamber at the foot of said chute, resiliently mounted fingers projecting into said chamber adapted to intercept and support 10 said articles, a plurality of gripping fingers projecting into said chamber adapted to grasp said article to accurately align it therein, a transfer arm, and means for moving said transfer arm to grip said article and means for spreading said 15 gripping fingers to release said article to allow said transfer arm to carry it through said chamber to a carton disposed adjacent thereto.

3. In a device of the class described, an inclined chute for feeding articles, cooperating fingers, 20 means for actuating said fingers to feed said articles one by one, a chamber at the foot of said chute, resiliently mounted fingers projecting into said chamber adapted to intercept and support 25 said articles, a transfer arm located above said 30 chamber, and means for lowering said transfer arm to grip said article and carry it through said chamber to a carton disposed therebelow.
